SURGICAL NEEDLE AND HOLDER

Mozes H. Marton, New York, N. Y.

Application October 20, 1933, Serial No. 694,405

11 Claims. (Cl. 128—303.18)

The improved surgical instrument comprising the present invention is primarily adapted for use as a depilator for the permanent destruction of hair bulbs which prevents further formation 5 or growth of the hair after the bulb has been destroyed. The invention is, with or without modification, capable of other uses and the same may be employed, for example, in the permanent destruction of tissue underlying the skin, or in 10 the coagulation or cauterization of tissue cells.

The principal object of the present invention is to provide an insulated surgical electrode, which is preferably in the form of a fine wire or needle, having its penetrating portion insulated, which enables one to cauterize, coagulate or destroy tissue cells located below the surface of the epidermis, without causing electrical injury to the epidermis itself.

With the uninsulated electrodes such as heretofore in use, that is to say, such electrodes as do not have the penetrating portion of the electrode insulated, this could not be done except at the sacrifice of a good deal of the overlying epidermis, which resulted in scarification and a change in 25 the pigmentation of the affected areas. Therefore, such results practically made futile the efforts to improve the appearance of the skin from an aesthetic point of view, and such results were also just as undesirable from a medical 30 point of view.

Other objects of the invention are to provide an improved surgical electrode and holder to form a cauterizing instrument wherein the members thereof may be simply assembled and conveniently operated, and furthermore to provide a marked improvement in the electrode unit itself.

These being among the objects of the present invention, the same consists of certain features 40 of construction and combinations of parts to be hereinafter described and then claimed with reference to the accompanying drawing illustrating one embodiment of the invention and wherein

Fig. 1 is a side elevation of the complete instrument including the electrode and its holder;

Fig. 2 is an enlarged section of a portion of the instrument shown in Fig. 1 on the line 2—2 thereof;

Fig. 3 is a still further enlarged cross-section 50 on the line 3—3 of Fig. 2;

Fig. 4 is an enlarged detail section of a portion of the holder;

Fig. 5 is a longitudinal section of the electrode unit which includes the electrode;

Fig. 6 is a longitudinal section of the tip-mem-

ber of the holder which is adapted to receive the electrode of Fig. 5, these two figures being on a different scale, and

Fig. 7 is a longitudinal section of the electrode unit which is adapted to form part of the electrode. 5

The tubular holder or handle 10 of the instrument is provided with a tapered tip-member 11 also of tubular form, and these are both composed of non-conducting material which may be 10 hard rubber. One end of the holder 10 is provided with a screw-threaded neck 10', the holder having a bore 10a. The holder and its tip-member may have a suitable length adapting them 15 for their use. Tip-member 11 is provided with an enlarged bore 11a to provide a skirt there-around and a smaller portion 11' of said bore is provided with a screw thread adapted to be engaged with the screw threaded neck 10'. That portion 11b of the bore which passes through the 20 tapered part of the tip-member 11 is of the smallest diameter and is adapted to receive the electrode to be hereinafter described. It will be seen that when the parts are threaded together the skirt portion around the large bore 10a of the 25 tip-member receives the adjacent larger portion of the holder 10, there being a slide fit between the two to permit the tip-member to be adjusted inwardly or outwardly on the holder 10. The outward position of the tip-member is shown in full lines in Fig. 2 and the inward position thereof is shown in broken lines. 30

In Fig. 5 an electrode unit is illustrated, it being shown in position on the instrument in Figs. 1 and 2. The electrode includes a thin metal tube 35 12 at the outside thereof and an interior layer or covering 13 of insulating material around and sheathing a fine wire 14 which forms the metallic 40 needle proper of the electrode, and the outer terminal of which slightly protrudes from the insulating covering 13 while its inner terminal protrudes for a greater distance beyond the corresponding end of the insulating covering 13. 45

The insulation 13 of the needle proper may be formed of any suitable insulating material and is 50 desirably formed from a length of glass tubing or other vitreous material which may be drawn or moulded into a small diameter so as to thoroughly encase, and to adhere to, the needle proper except for the two terminals referred to. 55

In Fig. 7 a unit is illustrated which may be characterized as a "needle unit" inasmuch as it may be manufactured as a separate article of manufacture, or the same may be combined with the outer metal tube 12 to provide a complete 55

electrode unit, in which case the inner terminal of the needle proper 14 is preferably connected by solder 18 with the metallic tube 12 so as to provide a suitable electrical connection between the two metal elements.

5 Suitable proportions with respect to the length and thickness of the electrode are important. The needle 14, as before stated, consists of a fine metallic wire, and it has been found in practice 10 that good results are obtained with a fine wire of a diameter of around 0.16 mm. The degree of protrusion of the point portion of the electrode proper beyond the insulation or layer 13 may in practice be approximately 1 mm. It is 15 important that the penetrating portion of the electrode which is directly behind the point portion, and follows it into the skin, should be suitably formed and of proper proportions. Therefore the insulation is tapered down at 13' to a 20 thickness that increases the diameter of the electrode to a barely perceptible degree.

Of course, the drawing, except Fig. 1, shows the parts of the instrument as exaggerated in size, 25 but the proportions substantially as stated are quite important.

Referring to Figs. 2 and 4 it will be seen that the threaded neck 10' of the holder 10 contains a 30 longitudinally split metallic tube 16, the slot 16' through which permits slight expansion or contraction of the tube 16. This tube is surrounded by a bushing 17 of suitable material which is 35 fitted tightly into the neck 10', and which reinforces and strengthens the neck. The split metal tube 16 is adapted to serve as a sort of clutch, inasmuch as when the tip member 11 is screwed 40 back to the position shown in broken lines in Fig. 2, the electrode, Fig. 5, may be slid into such tube and clutched thereby so as to retain the same, with the tube 12 and the tube 16 in electrical 45 contact. When so doing, the pliers used to insert the electrode are caused to grasp the outer end portion of the metal tube 12 which protects the insulation 13 against damage thereby. When the instrument is to be used for cauterization or 50 the like, the tip-member 11 is adjusted to the full line position shown in Fig. 2, or a little further if desired, to cover the metal tube 12 so that the hand of the operator which grasps the instrument is protected against electric shock. The 55 grip of the split tube 16 on the inner end of the electrode is sufficient to hold the same in using position and to permit the tip-member 11 of the holder to be screwed inwardly or outwardly relatively to the electrode without shifting the electrode with it. By screwing the tip-member inwardly to the position shown in broken lines in Fig. 2, a sufficient length of the metal tube 12 of the electrode is exposed so that pliers may be used by the operator to grip it and remove the 60 electrode at any time desired.

A suitable insulated electrical conductor 19 is shown, which is provided at one end with a suitable plug 19' for establishing a connection with the source of electricity. The inner end of the 65 conductor 19 is either secured by solder 16a, as shown in Fig. 4, or the end of the conductor may be plugged tightly into the adjacent end of the split tube and the conducting wires exposed and in electrical contact with the split metallic tube 70 16, as shown in Fig. 2. It will therefore be seen that when the patient being treated establishes in any well known manner a circuit through the source of electricity as by a suitable electrode in contact with another part of the body of the patient, that the current flows through the wires of 75

the conductor 19, the metallic sleeve or clutch 16, the metallic sleeve 12 of the electrode, the inner end of needle proper 14, and through the needle to that part of the body of the patient which is to be treated, whereby the exposed tip of the 5 needle proper may be used for cauterization or the like. At the same time the terminal portion 13a of the insulation around the needle protects the skin of the patient against injury by the current, and it being of such a small diameter, say 10 approximately twice that of the diameter of the needle proper, it can follow the extreme tip of the needle in penetrating the skin.

Obviously the invention may be modified more or less without departing from the scope of the 15 appended claims.

What I claim as new is—

1. A surgical electrode comprising an insulated penetrating portion adapted to penetrate and extend into the skin, said insulated electrode having an exposed uninsulated tip of smaller diameter than the penetrative portion adapted to contact with a portion of an underlying body to be destroyed, and means for applying a destructive electric current to said portion through said uninsulated tip the relation of the uninsulated tip and the penetrating portion being such that the portion to be destroyed may be affected locally without damaging overlying skin tissues.

2. A surgical electrode comprising a holder and an electrode proper comprising an insulated penetrating portion adapted to penetrate and extend into the skin and having at its extreme end an uninsulated portion adapted to contact with a tissue to be destroyed, and means for applying a destructive electric current to said tissue through said uninsulated end portion, said insulated portion protecting the skin penetrated from the effect of said electric current.

3. The method of destroying hair bulbs which underlie the skin to effect permanent removal of hair, which comprises passing an electrode through the skin so that its extreme end enters an underlying hair bulb, applying a destructive 45 electric current to said bulb through said extreme end while insulating the skin tissues overlying the hair bulb.

4. A depilatory electrode for the destruction of hair bulbs comprising an electrode adapted to initially puncture and penetrate the skin so that its extreme end enters an underlying hair bulb, and a thin coating of non-conducting material covering the penetrating portion of said electrode and terminating short of the extreme forward 55 end of the same whereby said electrode is insulated from the skin penetrated, and means for applying a destructive electric current to said bulb through the uninsulated forward end of said electrode.

5. A surgical needle-like electrode adapted for use in the permanent destruction of hair bulbs comprising an insulated penetrating portion having its extreme end exposed, said electrode being adapted to puncture and together with said insulation penetrate the skin so that the exposed end of the same enters an underlying hair bulb, and means for applying a weak destructive electric current to said bulb through said electrode.

6. A surgical electrode adapted for use in the permanent destruction of hair bulbs comprising an insulated penetrating portion having its extreme end exposed, the exposed end of said electrode being adapted to puncture the skin and enter an underlying hair bulb, the insulation of 75

said penetrating portion being adapted to pass through the puncture thus made in the skin by said exposed end and serving to insulate the contacting skin from said electrode, and means for applying a destructive electric current to said bulb through said exposed end.

5 7. A surgical needle adapted for use in the permanent destruction of hair bulbs comprising an insulated penetrating portion having its extreme 10 end exposed, said needle being adapted to puncture and together with said insulation penetrate the skin so that the exposed end of the same enters an underlying hair bulb, and means for applying a weak destructive electric current to 15 said bulb through said needle.

8. The method of destroying sub-surface tissue which comprises passing an electrode through the skin so that its extreme end enters said sub-surface tissue, applying a destructive electric 20 current to said tissue through said electrode while insulating the skin along the path of penetration from electrical injury.

9. A surgical electrode for the destruction of hair bulbs or like bodies underlying the skin, 25 which comprises a conductor having an uninsulated tip adapted to enter the skin and penetrate a hair bulb, said tip being of uniformly small diameter and an insulating coating of small but uniform thickness on said conductor from a point 30 closely adjacent said tip to a point which lies outside the skin when the tip penetrates a hair bulb for destroying the same, whereby the electrode may be inserted into the skin without forming a conical opening therein and a destructive 35 electric current may be applied locally to a hair bulb without affecting overlying tissues.

10. A surgical electrode adapted for use in the permanent destruction of hair bulbs and like bodies underlying the skin which comprises an elongated conductor of small diameter having an uninsulated tip adapted to penetrate the skin 5 and extend into a hair bulb, a thin insulating coating on said conductor from a point closely adjacent said tip to a point which lies outside but adjacent the skin tissues when the tip is inserted into a hair bulb for use, whereby a 10 destructive electric current may be applied to the bulb without affecting overlying tissues and a thicker insulating coating extending backward on the conductor from the point last recited, the junction between the insulating coating of different thickness serving as a gauge to facilitate the 15 insertion of the electrode for the proper distance to penetrate a hair bulb.

11. A surgical electrode for the destruction of hair bulbs or like bodies underlying the skin 20 which comprises a conductor having an uninsulated tip adapted to enter the skin and penetrate a hair bulb, an insulating coating on said conductor from a point closely adjacent said tip backward whereby the electrode may be inserted 25 into the skin in such manner that the tip enters a hair bulb and the coating insulates the tissues overlying such bulb so that a destructive electric current may be applied locally to the bulb without affecting such tissues, and means on the 30 electrode at a point which lies outside but adjacent the skin when the electrode is inserted for use to serve as a gauge for facilitating the accurate insertion of the tip into a hair bulb.
